UNITED STATES PATENT OFFICE.

MILTON S. ERLANGER, OF NEW YORK, N. Y., ASSIGNOR TO THE B. V. D. COMPANY, A CORPORATION OF DELAWARE.

UNDERGARMENT.

1,110,761.

Specification of Letters Patent. Patented Sept. 15, 1914.

Application filed February 6, 1914. Serial No. 816,885.

To all whom it may concern:

Be it known that I, MILTON S. ERLANGER, a citizen of the United States, and a resident of the borough of Manhattan, city, county, and State of New York, have invented certain new and useful Improvements in Undergarments, of which the following is a specification.

My invention relates to undergarments and more particularly to that type of such garments commonly known as union suits and has for its object to improve the crotch construction thereof. In union suits of the kind to which the present invention relates numerous attempts have been made to improve the crotch construction, all of which have resulted in a garment, either closed in the crotch with the posterior opening running down into one of the legs or a garment entirely open in the crotch and provided with fastening devices to maintain the crotch portion of the garment in a closed condition or in which the trunk length of a garment of a given size is disturbed in order to provide garment openings of the required dimensions, this latter structure resulting in a dropping of the crotch and a consequent uncomfortable bunching of the material at said crotch when the garment is worn. My improvement overcomes all of these objectionable features and provides a garment in which a portion of the fabric composing the crotch portion of the undergarment will at all times be interposed between the person of the wearer and his outer garments, thus providing all the advantages of the so-called closed crotch constructions.

My invention further avoids the necessity for using fastening devices to maintain the crotch portion of the garment in an effective position and also maintains the trunk length in each given size of garment at the recognized most effective standard to secure a perfect and comfortable fit and further provides front and posterior garment openings of ample dimensions for a comfortable positioning of the garment in all attitudes of the wearer all as will be explained in detail in the description hereinafter.

In the drawings which illustrate an example of my invention, Figure 1 is a front

view of the garment and Fig. 2 is a detail rear view thereof.

Referring to said drawings A represents the left leg and B the right leg both of which are connected in the neighborhood of the waist line with the body C, the illustration showing a waist band D of relatively elastic material located between the legs A and B and the body C and which may be omitted as it forms no part of the present invention.

The garment at the front is open and is provided with hems E and F extending lengthwise of and forming the edges of said front opening and provided respectively with button holes E' and buttons F' whereby the garment is closed at the front. The hem E at its lower end overlaps the lower end of the hem F and is secured thereto by transverse stitches G and G' the former being located approximately in line with the leg seam A' and the latter being located at a short distance above this point. It will thus be seen that the front opening extends from the stitches G' to the neck of the garment and that the fabric forming the edges of said front opening is permanently united in the crotch as clearly shown in Fig. 1 of the drawings. The inner edge B' of the right leg B is free throughout substantially its entire length and extends from the waist line at the rear of the garment downwardly and toward the front of the garment and then upwardly at the front and is united with the hem F at a point considerably above the crotch and designated on the drawings as H. A flap I has its one edge secured by stitches J to the inner edge of the left leg A from a point near the waist line to the stitches G at the crotch portion of the garment and then extends transversely parallel with said stitches which pass through said flap I and secure the same in the garment at this point. The said edge of said flap is continued up at the front of the garment to a point above the crotch and lower end of the front opening and is fastened to the button hem F at J'. The upper front end of said flap I is secured in the garment by a row of stitches K which extend downwardly at an incline to the but-

ton hem F or to the front opening of the garment and are located in the neighborhood of the point H at which the inner edge of the leg B becomes united with the hem F. The opposite edge of said flap I is free from a point near the waist region of the garment at the rear to the lower end of the row of stitches K at the front and in the normal position of the garment when worn overlaps the inner edge of the right leg B.

If desired, a button hole L having a suitably located coöperating button may be provided at the rear of the garment at a point above the crotch to maintain the rear portion of the flap I in its closed position. No other fastening devices are required as the flap automatically assumes and maintains its normal position to close the posterior and crotch openings. With this construction a posterior opening is produced which extends from a point near the waist line at the rear to a point above the crotch at the front of the garment so that the front opening of the garment and said posterior opening extend beyond each other at the front as clearly shown in Fig. 1 of the drawings. In this manner an undergarment is provided which is provided with a front opening of increased dimensions to permit the garment to be more readily put on and taken off than ordinary garments and in which a posterior opening of maximum dimensions is secured so as to permit a comfortable adjustment of the garment in all positions of the wearer. The inclined stitches K permit a maximum spreading of the garment to open the posterior opening during a sitting position of the wearer, this spreading being possible from the upper end of said stitches K. The above results are obtained without disturbing or changing the trunk length which has by experience given the best results and most comfortable fit in any given size of garment, or in other words the crotch is not dropped to secure a posterior opening of increased dimensions and the bunching of material resulting from such a proceeding is consequently entirely avoided. In addition to the above it will be seen that when the garment is worn and even when the front portion thereof is opened the flap I, particularly at the crotch will at all times be interposed between the wearer and his outer garment. All the advantages of a closed crotch garment are thus secured without sacrificing any of the advantages which an open crotch garment may have. By extending the front and posterior openings beyond each other at the front the garment is provided at the front crotch region with two openings located side by side. In some cases the stitches G' may be omitted and the front opening thus still further increased in dimensions.

Various changes in the specific construction shown and described may be made within the scope of the claims without departing from the spirit of my invention.

I claim:

1. An undergarment having a permanently closed crotch and a front opening extending downwardly from the neck opening to a point adjacent to the crotch, and a posterior opening extending from a point near the waist line at the rear to a point above the crotch in front and above the lower end of said front opening. 70

2. A union suit having a front opening from the neck to a point adjacent to the crotch, the fabric forming the edges of said opening being permanently united in the crotch and a second opening extending from the waist line at the rear to a point at the front of the garment nearer the neck than the crotch and a flap adapted to cover said second opening. 80

3. An undergarment having a permanently closed crotch and a front opening extending adjacent thereto, and a posterior opening extending from a point near the waist line at the rear to a point above the crotch at the front, so that the two openings extend one beyond the other at the front of the garment, a flap for covering said posterior opening having its one end secured in said garment adjacent to the waist line at the rear and its other end located adjacent to the terminating end of said posterior opening at the front of the garment and a row of stitches inclined downwardly relatively to said front opening for securing said other end of said flap in the garment. 90

4. An undergarment having a permanently closed crotch, a front opening extending downwardly from the neck opening to a point below the waist line, a posterior opening extending from a point near the waist line at the rear to a point above the crotch at the front of the garment and a flap for covering said posterior opening having its opposite ends and one edge secured in the garment and its other edge free, said free edge of said flap extending to a point at the front of the garment above the crotch and out of longitudinal alinement with said front opening. 105

5. An undergarment having a permanently closed crotch and a front opening extending downwardly from the neck opening to a point below the waist line, a posterior opening extending from a point near the waist line at the rear to a point above the crotch at the front of the garment, the two openings being out of longitudinal alinement at the front of the garment, a flap for covering said posterior opening having its one end secured in said garment adjacent to the waist line at the rear and its other end 110

located adjacent to the terminating end of
said posterior opening at the front of the
garment and a row of stitches inclined
downwardly relatively to said front open-
5 ing for securing said other end of said flap
in said garment at the front thereof.

In testimony whereof, I have hereunto set

my hand in the presence of two subscribing
witnesses.

MILTON S. ERLANGER.
